CLAIM

The ornamental design for an electronic cigarette, as shown
and described.

DESCRIPTION

FIG. 1 is a perspective view of an electronic cigarette;
FIG. 2 is a front view of the electronic cigarette;
FIG. 3 is a rear view of the electronic cigarette;
FIG. 4 is a bottom side view of the electronic cigarette;
FIG. 5 is a top view of the electronic cigarette;
FIG. 6 is a left side view of the electronic cigarette; and,
FIG. 7 is a right side view of the electronic cigarette.
The evenly spaced broken lines in the drawings depict
portions of the electronic cigarette that form no part of the
claimed design. The dash-dot-dash lines represent boundar-
ies of the claimed design.

1 Claim, 7 Drawing Sheets

Related U.S. Application Data

division of application No. 29/710,943, filed on Oct. 28, 2019, now Pat. No. Des. 901,758, which is a division of application No. 29/662,843, filed on Sep. 10, 2018, now Pat. No. Des. 868,360, which is a division of application No. 29/592,199, filed on Jan. 27, 2017, now Pat. No. Des. 830,625.
